MACHINE FOR MANUFACTURING COAXIAL PAIRS FOR TELECOMMUNICATION CABLES

Florimond A. J. Deuchet, Paris, France, assignor to Societe Alsacienne de Constructions Mechaniques, Paris, France, a corporation of France

Application August 4, 1950, Serial No. 177,592

Claims priority, application France
September 3, 1949

1 Claim. (Cl. 29—203)

1
This invention is for improvements in or relating to a machine for manufacturing co-axial pairs of conductors for telecommunication cables and more particularly the provision of means for arranging spaced insulating discs upon a centrally disposed conductor.

In a particular type of co-axial pairs having a discontinuous insulation, which are employed in telecommunication technique, the pair consists of an inner (or "central") conductor arranged centrally inside an outer cylindrical conductor. The inner conductor is centrally arranged within the outer conductor by means of discs of insulating material spaced apart at regular intervals.

For the construction of these pairs, machines are generally employed in which a mechanism is operable firstly to arrange regularly, on the central conductor, insulating discs which have been previously cut out and perforated to the necessary dimensions and secondly to form the outer cylindrical conductor, generally from a suitably cut out tape and forming it into a cylindrical tube which forms a covering for the insulating discs. The central conductor usually consists of a single wire of circular cross-section.

According to one object of the present invention there is provided the machine for manufacturing co-axial pairs of telecommunication cables having a discontinuous insulation, wherein insulating discs are fed by a duct into a channel arranged at right angles to the direction of the said rectilinear duct, said discs being pushed into the channel by means of a piston to meet a knife which splits the disc radially and thereafter pushes the slit discs straddling the knife along the said knife and finally places them on the central conductor which is carried upon a wheel. The rim of this wheel has a thickness about equal to the diameter of the central conductor, so that the said rim can also be straddled by the slit piston.

Other features of the machine which is the object of the invention comprise essentially a block inside which are provided a curved passage adapted to receive the wheel carrying a central conductor and a rectilinear guiding channel located at the outlet thereof and forming an extension of the said passage, a knife fixed relatively to said block, in such a manner that one of

its edges extends substantially parallel to the guiding channel and is disposed within the said channel, and in the vicinity of which there is provided the above-mentioned duct for feeding discs into said channel, the said duct being disposed substantially at right angles to the axis of the said channel, a piston slideable in said channel, means for imparting a reciprocating movement to said piston and means for causing discs supplied by said duct to enter said channel at regular intervals.

2
During the rectilinear motion of the slit discs the edges of the slit are brought into contact with the central conductor then carried by the wheel at a point where the conductor is intentionally curved. The edges of the slots in the discs open and the discs are arranged to straddle the conductor and the wheel carrying it, the discs being pushed by the piston somewhat further than the point where the said conductor ceases to be carried by the wheel.

The invention will be more particularly described with reference to the accompanying drawings in which:

Figure 1 illustrates in elevation and partly in section along line I—I of Figure 2 a machine constructed in accordance with the present invention.

Figure 2 is a sectional plan view in a plane perpendicular to that of Figure 1, and passing through the line II—II thereof.

Figures 3 and 4 are transverse sections on the lines III—III and IV—IV of Figure 2.

Figures 5 and 6 are respectively elevation and section views of the knife represented at 12 on Figure 1.

Referring to the drawings, the machine illustrated comprises a plate 1 arranged to support a wheel 2 provided with a groove at its periphery on which rests a central conductor 3 of a co-axial pair in its path in the direction of the arrow 4.

On the plate 1 is mounted a rectangular block 5 at one end of which are mounted two blocks 6a and 6b. The block 6a only is shown on Fig. 1, as the projection of 6b on the plane of said Fig. 1 coincides with that of 6a. The central plane of the wheel 2 constitutes a plane of symmetry for the block 5 and coincides with the plane of contact of the two blocks 6a and 6b. A longitudinal channel 7, which is substantially of the same diameter as an insulating disc is provided inside

3

the block 5; two grooves, of semi-circular section, are provided on the opposite faces of the blocks 6a and 6b and these grooves form a second channel 8 extending from the channel 7. On Fig. 2 the parts of 6a and 6b at the left of the axis of the wheel 2 are supposed to be removed, to make the mechanism visible.

Inside the channel 7 a piston 9 is mounted, capable of sliding, which, at the end of its stroke, uncovers a rectilinear feed duct 10 into which insulating discs 11, and 11a, may be fed by a device known per se. The insulating discs are thus delivered one at a time in front of the piston 9.

A knife blade 12 is arranged between parts 6a and 6b and extends into the channel 8 so that one longitudinal edge thereof extends a little beyond the length of the channel 8 and one of its free ends is located on the rim of the feed duct 10. The piston 9 is provided with a longitudinal groove 9a of such dimensions that said piston 9 can slide in the channel 8 without fouling the knife 12. By moving the piston 9 towards the knife by means which will be hereinafter described, the piston 9 pushes an insulating disc 11 towards the knife 12 which slits the disc radially. The continued movement of the slit insulating disc under the action of the piston 9, causes the said disc to straddle the central conductor 3 at the end of the curved part thereof and to be further pushed and carried along by said conductor.

In order to prevent the disc 11 from failing to assume or preserve a suitable disposition in the duct 7 and to prevent it falling down in front of the piston 9, a suitable guiding device is provided. To this effect the blocks parts 6a and 6b are wedge-shaped and are each provided with an oblique groove 13 wherein a catch 14 can move.

These catches are designed so as partly to complete the channel 8 and to provide with the feed duct 10 a housing for the disc 11, as will be readily seen from Figure 2. With such an arrangement the insulating disc 11, pushed by the piston 9 is clamped between the end of the piston and the two movable catches 14 where it is held in a correct position in which to be presented to the knife 12.

The bent-over end of a yieldingly controlled rod 16 secured by a screw 17 to a sleeve 18 which surrounds the piston 9 is adapted to engage with a notch 15 in each catch 14. A spring 19 interposed between the sleeve 18 and the end of block 5 tends to hold the catches 14 against block 5, a position in which they partly fill the channel 8 in the circumstances described in the preceding paragraph.

Through the medium of the piston 9, the disc 11 pushes the catches 14 which, in their motion along the inclined face of each wedge-shaped block 6a or 6b, are separated to free the central channel 8 so as to allow the passage of the insulating disc. The catches remain apart and bear on the piston 9 as long as the same is disposed in the channel 8.

During the return stroke of the piston 9, the catches resume their position of partially blocking the channel 8 under the action of the spring 19, which, by pushing back the ring 18, brings the catches back into their initial position under the influence of the yielding rods 16. The piston 9 upon finishing its return stroke, uncovers the feed duct 10 and permits a new insulating disc to fall in front of the piston in the space limited by the catches 14 and the end of the piston.

The reciprocating motion of the piston is de-

rived from the angular displacement of a lever 20, moved by any device of a known type, for instance a cam system or a connecting rod and crank.

In order to provide a sufficient time for the fall of the insulating disc 11 into its housing at the end of the piston stroke, the piston is connected to the lever 20 through a lost motion device.

The motion of this lever is imparted to the piston 9 through two bearing rings 21 and 22 having a certain play between them, allowing the piston to remain at rest for a suitable period of its stroke. The piston is mounted in friction rings 23, 24 and 25 formed of self lubricating bodies, the purpose of which is to facilitate the displacement of the piston by decreasing the risk of seizing.

In order to prevent any rotational movement of the piston about its axis during longitudinal displacement thereof a pin 27 is arranged to engage with the longitudinal groove 9a of piston 9.

The leading end of the piston 9 is flattened as shown at 28 to prevent an insulating disc 11a waiting to drop into the channel 10 from being struck away by the end of the piston during its displacement.

What is claimed is:

30 In a machine for mounting spaced insulating discs on the inner conductor of a coaxial pair, a rectilinear disc feeding duct, a disc holding chamber at one end of said duct into which the discs are fed successively and retained momentarily each with its axis perpendicular to the direction of feed in the duct, a first rectilinear channel opening into the chamber on one side thereof and coaxial with the disc in said chamber, a slit piston mounted to slide in said first channel and to push the discs out of said chamber transversely to the direction of feed in said duct, a disc guiding device communicating with said chamber on the other side thereof and positioned to guide the discs when pushed out of said chamber and to define a path of movement therefor, a second rectilinear channel positioned in alignment with said first channel beyond said guiding device in the path of movement defined by said guiding device for said discs when pushed by said piston, said guiding device and second channel comprising a pair of blocks having grooved contacting surfaces defining said second channel and inclined outer faces diverging in a direction away from said chamber, a pair of movable catches each positioned to slide on one of said inclined faces between an obstructing position adjacent said chamber at which said catches obstruct said path of movement and a remote position at which said catches are separated by said blocks to leave said path unobstructed, first resilient means yieldably urging said catches into said obstructing position, and second resilient means urging said catches into sliding contact with said inclined faces, a knife projecting into said second channel and path of movement of the discs and having a cutting edge extending parallel thereto from a point adjacent said chamber to a point beyond said second channel, a peripherally grooved wheel of thickness substantially equal to and positioned to support the inner conductor adjacent said point beyond said second channel in alignment therewith, and means for reciprocating said piston between a retracted position inside said first channel and a position at least partly overlap-

The reciprocating motion of the piston is de-

75

ping said wheel, whereby the stroke of said piston between said two positions thereof will cause said piston to push a disc positioned in said chamber successively into contact with said catches, along said path of movement in opposition to said first 5 resilient means while said catches slide along said inclined faces, through said second channel along said cutting edge and onto the inner conductor.
